UNITED STATES PATENT OFFICE.

RALPH JAMES RILEY, OF PORTLAND, MAINE.

SPROCKET WHEEL.

1,421,832.

Specification of Letters Patent.

Patented July 4, 1922.

Application filed September 13, 1921. Serial No. 500,304.

To all whom it may concern:

Be it known that I, RALPH J. RILEY, a citizen of the United States, and a resident of Portland, in the county of Cumberland and State of Maine, have invented certain new and useful Improvements in Sprocket Wheels, of which the following is a specification.

My invention relates to sprocket wheels having a continuous rim with pockets spaced apart and cut from its periphery inwardly, having rectangular sides and between said pockets an annular channel with flaring sides for receiving a cable to which buttons are secured and adapted to drop into said pockets, and has for an object to provide a replaceable wearing shoe therefor adapted to be fitted into dove tails or guideways at the ends of the pockets to receive the thrust 20 and wear when in operative contact with the buttons.

In sprocket wheels of this type, heretofore, the buttons secured to the cable have operated against the ends of the pockets, there- 25 by wearing the end faces of the pockets, and in time requiring the wheel to be replaced.

An object of my invention is to provide wearing shoes to be secured to the sprocket 30 wheel at the points of contact of the buttons with the wheel so that the shoes which are readily replaceable will wear and the sprocket wheel will be free from wearing contact with the buttons.

Another object of my invention is to pro- 35 vide wearing shoes which are readily removable, and means for securing said shoes in operative position in the sprocket wheel.

With these and other objects in view, my 40 invention consists of the novel construction and arrangement of parts hereinafter more particularly set forth.

In the drawings, illustrating my invention, similar characters of reference indicate 45 corresponding parts, and in which—

Fig. 1 is a view in side elevation of my invention.

Fig. 2 is a plan view of a portion of the sprocket wheel and cable.

Fig. 3 is a view in vertical section through the perimeter of a portion of the rim. In this view, the rim is adapted to receive the wearing shoe inserted from the inner edge of the rim.

Fig. 4 is a view in vertical cross section taken on the line 4—4 of Fig. 3.

Fig. 5 is a view in vertical section taken through the perimeter of a portion of the rim with the rim adapted for inserting the wearing shoe inwardly from the outer 60 periphery of the rim.

Fig. 6 is a view in vertical cross section taken on the line 6—6 of Fig. 5.

Fig. 7 is a view in cross section of the rim taken between a pocket and a spoke of 65 the wheel.

In the drawings illustrating my invention, I have shown my improved sprocket wheel 1 driven by a cable 2 to which latter a series of equally spaced buttons 3 are 70 secured. The sprocket wheel 1 is provided in its periphery with pockets 4 equally spaced apart a distance similar to the spacing of the buttons 3. The pockets 4 are preferably rectangular in cross section with 75 sloping end faces and parallel sides 5. Between said pockets the sprocket wheel is provided in its periphery with an annular channel 6 having flaring sides 7.

The pockets 4 have the dove tailed grooves 80 or guideways 8 formed in their end faces adapted to accommodate my improved wearing shoes 9. The wearing shoes 9 as shown in Figs. 3 and 4, are inserted into the guideways 8 from the inner face of the rim. 85

These shoes are tapered, the narrow outer end of each shoe being channeled to form a continuation of the channel 6 for receiving the cable 2, and have beveled side edges 10 thereby holding the wearing shoe se- 90 surely in the guideways 8. For locking the wearing shoe 9 in position in guideways 8, I have provided on each side face 5 of the pockets 4 at a corresponding point thereof, a rectangular hole 12, which hole aligns 95 with a rectangular hole 13 provided in the wearing shoe 9 when the said shoe is in position in guideways 8. A tapered pin 11 is adapted to be inserted in the rectangular holes thus formed in the side faces 5 and 100 the wearing shoes 9 and to be locked there- in by means of the nut 14 located at the small end of the pin 11. The wearing shoes 9 are each additionally locked in the guide- 105 ways 8 by means of a plate 15 secured to the inner face of the rim by means of the bolts 16. These plates close the guideways 8 so that the shoes cannot be lost therefrom and in addition render it impossible to remove the wearing shoes without first re- 110 moving the plates.

In the Figs. 5 and 6 I have shown a modi-

ification of my invention with a wearing shoe 9^a adapted to be inserted in the guideways 8^a inwardly from the outer edge of the rim, the guideways 8^a being tapered inwardly to conform to this type of wearing shoe. The wearing shoes 9^a have each a rectangular opening 13^a therein, in which the head of a bolt 15^a is inserted, the said bolt extending through a hole in the plate 14^a securely locks the shoe 9^a in operative position in the guideways 8^a. Tightening of the nut 10^a on the bolt 15^a will draw the shoe 9^a inwardly, thereby impinging it in the tapered guideways 8^a.
15 It will be understood that the wearing shoes thus positioned will receive the wear and tear when the buttons are in operative contact therewith and for this reason are made readily replaceable. In addition, the 20 wearing shoes can be manufactured cheaply and can therefore be discarded when they become worn and new shoes substituted at a small cost. By the utilization of such wearing shoes the wear and tear on the 25 sprocket wheel is greatly lessened and its life is prolonged thereby.

Having thus described my invention, I now claim—

1. A sprocket wheel having pockets 30 spaced apart formed in the periphery of the wheel and between said pockets an annular channel, said pockets having guideways formed therein and wearing shoes adapted to fit into said guideways, said wearing 35 shoes being tapered and each provided with a rectangular hole therethrough aligning with rectangular holes in the side faces of the pocket for inserting a tapered pin there-

in for locking the wearing shoe in the guideways.

2. A sprocket wheel having pockets spaced apart formed in the periphery of the wheel and between said pockets an annular channel, said pockets having guideways formed therein and wearing shoes adapted to fit into 45 said guideways, said wearing shoes being tapered and each provided with a rectangular hole therethrough aligning with rectangular holes in the side faces of the pocket for 50 inserting a tapered pin therein for locking the wearing shoe in the guideways, and each additionally locked in the guideways by means of a plate secured to the inner face of the rim.

3. A sprocket wheel having pockets spaced 55 apart formed in the periphery of the wheel and between said pockets an annular channel, said pockets having guideways formed 60 therein, and wearing shoes adapted to fit into said guideways, said wearing shoes being tapered and each secured in the guideways by means of a plate locked against the inner face of the rim.

4. A sprocket wheel having pockets spaced 65 apart formed in the periphery of the wheel and between said pockets an annular channel, said pockets having guideways formed 70 therein and wearing shoes adapted to fit into said guideways, said wearing shoes being tapered, and each of said wearing shoes 75 having a rectangular opening therein for receiving the head of a bolt, said bolt extending through a hole in the plate for locking the said shoe in operative position in the guideways.

RALPH JAMES RILEY.
